DOLL

Thelma A. Pulham, Park Ridge, Ill.

Application August 20, 1948, Serial No. 148,228

Term of patent 7 years

(Cl. D34—4)

To all whom it may concern:

Be it known that I, Thelma A. Pulham, a citizen of the United States, residing at Park Ridge, in the county of Cook and State of Illinois, have invented a new, original, and ornamental Design for a Doll, of which the following is a specification, reference being had to the accompanying drawing, forming a part thereof.

Fig. 1 is a front view of a doll showing my new design; and

Fig. 2 is a side view showing the doll from the left side.

The essential features of my design reside in the portion shown in full lines.

I claim:

The ornamental design for a doll, substantially as shown and described.

THELMA A. PULHAM.
